Patented Apr. 4, 1972

223,245

RECLINING CHAIR

Morton I. Thomas, Monroe, N.Y.
(125 South St., Passaic, N.J. 07055)

Filed Nov. 16, 1970, Ser. No. 26,021

Term of patent 14 years

Int. Cl. D6—02

U.S. Cl. D15—11

FIG. 1

FIG. 2

FIG. 3

FIG. 4

FIG. 5

FIG. 1 is a perspective view of a reclining chair, showing my new design;

FIG. 2 is a side elevational view thereof;

FIG. 3 is a front elevational view showing one of the two identical sides;

FIG. 4 is a rear elevational view; and

FIG. 5 is a plan view thereof.

I claim:

The ornamental design for a reclining chair, substantially as shown and described.
